PETRIE, OF NEW YORK, N. Y.

WHISTLE

Application filed January 30, 1929. Serial No. 336,140.

This invention relates to whistles and particularly to devices of this class composed of relatively movable parts whereby the interior of the whistle structure may be maintained in a clean and sanitary state at all times; and the object of the invention is to provide a whistle device having a substantially cylindrical sound chamber at one end thereof and a mouth piece portion extending tangentially with respect to the sound chamber, part of the mouth piece and sound chamber being movable with respect to the whistle device to expose the interior of the sound chamber and mouthpiece for cleaning or other purposes; a further object being to provide a whistle device of the structure set forth wherein the detachable or movable part constitutes a top plate of the whistle device and is arranged in common alinement with the upper edge of the main unitary part of the whistle structure to produce a neat and finished appearance, means being provided for retaining the detachable or movable part in closed position; and with these and other objects in view, the invention consists in a device of the class and for the purpose specified which is simple in construction, efficient in use and which is constructed as hereinafter described and claimed.

The invention is fully disclosed in the following specification, of which the accompanying drawing forms a part, in which the separate parts of my improvement are designated by suitable reference characters in each of the views, and in which:—

Fig. 1 is a transverse, sectional view through one form of whistle made according to my invention.

Fig. 2 is a plan view of the structure shown in Fig. 1 with part of the construction broken away.

Fig. 3 is a front view of the whistle device.

Fig. 4 is a perspective detail view of the removable part of the device shown in Figs. 1 to 3 inclusive.

Fig. 5 is a side and sectional view of a whistle similar to that shown in Fig. 1 and illustrating a modification.

Fig. 6 is a section on the line 6—6 of Fig. 5.

Fig. 7 is a sectional detail view of another form of whistle device which I employ.

Fig. 8 is a section on the line 8—8 of Fig. 7; and,

Fig. 9 is a view similar to Fig. 1, showing another modification.

The invention described and claimed herein is an improvement on the structure shown and described in a prior patent granted to me October 23, 1928, and bearing Patent No. 1-688,349. In my present invention I have devised means for adapting the broad principle of the detachable part whistle to a whistle structure of more or less conventional form, so as to render this conventional type of whistle more sanitary and practical in use, and also simplify the manufacture thereof.

The particular type of whistle disclosed in the accompanying drawing is of the substantially cylindrical type wherein the mouthpiece projects tangentially with respect to the wall of the sound chamber of the whistle. In Figs. 1 to 4 inclusive, I have shown one form of construction or one method of carrying my invention into effect.

In Fig. 1, I have shown a whistle device comprising a substantially cylindrical sound chamber 10, and projecting therefrom is a mouthpiece part 11 arranged tangentially with respect to the chamber 10. In the construction shown, the chamber 10 is formed from a substantially circular wall 12 and flat side walls 13, the latter extending onto the mouthpiece portion and the lip extension 14 which is continuous with the wall 12 as clearly seen in said figure.

At 15, I have shown an insert piece which is substantially V-shaped in form and is arranged in the mouthpiece 11 to direct the air upwardly to a comparatively narrow discharge 16 into the sound chamber and also to complete the formation of the cylindrical chamber by the curved extension 15^a. The circular wall 12 terminates at its upper end as seen at 17 at a point rearwardly of the central portion of the chamber 10, and detachably mounted in connection with the upper open end of the whistle structure is a closure plate 18 having at its rear end a rectangular aperture 19 so arranged with respect to the 100

discharge 16 as to produce the proper sound or whistle tone.

The plate 18 has downwardly extending side walls 20, the forward end portions of which have inclined lower surfaces 21 to rest upon the inclined wall of the part 15. These walls are flared outwardly at their lower ends to form a slight dove-tailed structure cooperating with the inwardly flared side walls 13 at the mouthpiece portion of the whistle device so as to retain the plate 18 against displacement. This structure is clearly seen in Fig. 3 of the drawing.

The rear end of the plate 18 is provided at its lower surface with an inwardly projecting flange or lip 22 which is adapted to extend beneath the wall 12 at its end 17 so as to support the inner end of the plate 18 against displacement, and further to provide a seal preventing the discharge of air from the chamber 10 except through the aperture 19. It is also preferred that the forward end portion of the plate 18 be provided with an upwardly pressed and substantially arc-shaped lip piece 23 which also forms a finger piece facilitating the removal of the plate 18 for cleaning or other purposes, it being understood that the plate 18 is inserted and removed by sliding the same forwardly and backwardly with respect to the whistle device.

It will also be understood at this time, that while I have indicated in the several figures in the accompanying drawing, that the parts of the whistle device are made from sheet metal or other sheet material such as rubber, bakelite, celluloid and other materials of this class, that the several parts constituting the whistle proper and the movable or removable member or plate may be cast or molded in accordance with conventional processes.

In Figs. 5 and 6 of the drawing, I have shown a slight modification, and in this figure, like references will indicate like parts, the only structural difference being that the side walls 13 at the mouth end portion of the whistle device are made straight rather than inclined inwardly as in Fig. 3, and the side walls 20 of the plate 18 are correspondingly formed. Instead of slidably engaging the plate 18 with the whistle device, I pivot the same thereto at the mouth end portion of the whistle by forming inwardly pressed beads or pivots 24 on the walls 13, and 25 on the walls 20 as clearly seen in Fig. 6 of the drawing, or these pivots may be made in any desired manner such as by the use of pivot pins. In this construction, the free inner edge of the plate 18 instead of having the projecting lip 22, is provided with a slight bead or extension 26 which cooperates with the edge 17 of the wall 12 to frictionally retain the plate 18 in closed position.

In all forms of the whistle device, a ball 27 is arranged in the sound chamber of the whistle device and is free to reciprocate there-

in in the operation of the whistle as in other devices of this class. It is also preferred that a supporting eye or loop 28 be attached to one wall of the whistle body proper.

In Figs. 7 and 8 of the drawing, I have shown another modification, wherein the sound chamber 10^a of the whistle device is modified in its construction in that the circular or cylindrical wall 12^a extends upwardly to form the contracted discharge 16^a and also the inclined wall 29 of the mouthpiece, which wall also constitutes the bottom wall of said mouthpiece.

In this construction, the side walls 13^a of the whistle device correspond to the contour of the sound chamber and mouthpiece, said side walls at the mouthpiece end of the whistle device being straight as seen in Fig. 8 of the drawing; and their upper edges are fashioned to form, on the inner faces thereof, grooves 30 to receive a top closure plate 31 which is slidably mounted in the grooves 30 in the operation of attaching and detaching the same, the inner end portion of the plate 31 having an aperture 32 which is similar to the aperture 19, and the inner end of said plate having a projecting lip 33 which rests under the wall 12^a to form a concealed joint at said end of the plate.

In Fig. 9 of the drawing, I have shown another modification which is substantially similar to the structure shown in Fig. 7 especially with respect to the general contour of the whistle device. In this structure, however, the sound chamber 34 consists of five angularly disposed side walls 35, 35^a, 35^b, 35^c and 35^d, the wall 35^d extending forwardly and downwardly to form the lower wall 35^e of the mouthpiece 36, the chambers formed by straight side walls 37 also extending onto and forming the side walls of the mouthpiece 36.

With this form of whistle body structure, it will be seen that the same may be readily molded, cast or even stamped from sheet material of any kind or class, especially in that the walls 35 and 35^d extend upwardly in a straight vertical line. In this construction, I employ a removable top closure plate 38 which is substantially similar to the plate 18 and includes side walls 39 fashioned at the mouthpiece end to conform with the contour of the mouthpiece and dove-tailed as in the structure shown in Fig. 3, the inner end of the plate 38 having a downwardly extending flange 40 which bears against the wall 35. If desired, the upper end of said wall may be turned inwardly to a slight extent as seen at 41 to retain the plate 38 against displacement. This plate has a sound aperture 42 arranged adjacent the contracted discharge 43 at the inner end of the mouthpiece 36.

From the foregoing, it will be apparent that my invention is not necessarily limited

to the specific shape or form of the sound chamber of the whistle device herein shown and described, nor am I necessarily limited to any particular shape or form of the movable whistle part, and various other changes in and modifications of the construction herein shown and described may be made within the scope of the appended claims without departing from the spirit of my invention or sacrificing its advantages.

Having fully described my invention, what I claim as new and desire to secure by Letters Patent, is:

1. A whistle device composed of two independently formed parts, one of said parts forming the sound chamber and including an angularly disposed mouthpiece portion, and the other part comprising a plate co-operating with said sound chamber and mouthpiece portion to complete the formation thereof and being movable relatively thereto to expose the interior of the sound chamber and mouthpiece for cleaning or other purposes, said plate including a discharge aperture disposed in predetermined relation with respect to the sound chamber and the discharge at the inner end of the mouthpiece, and means forming a seal between the adjacent walls of said plate, sound chamber and mouthpiece.

2. A whistle device composed of two independently formed parts, one of said parts forming the sound chamber and including an angularly disposed mouthpiece portion, and the other part comprising a plate co-operating with said sound chamber and mouthpiece portion to complete the formation thereof and being movable relatively thereto to expose the interior of the sound chamber and mouthpiece for cleaning or other purposes, said plate including a discharge aperture disposed in predetermined relation with respect to the sound chamber and the discharge at the inner end of the mouthpiece, and means forming a seal between the adjacent walls of said plate, sound chamber and mouthpiece and for preventing the accidental displacement of said plate.

3. A whistle device composed of two independently formed parts, one of said parts forming the sound chamber and including an angularly disposed mouthpiece portion, and the other part comprising a plate co-operating with said sound chamber and mouthpiece portion to complete the formation thereof and being movable relatively thereto to expose the interior of the sound chamber and mouthpiece for cleaning or other purposes, said plate including side wall members co-operating with the side wall members of the mouthpiece and said sound chamber, and co-operating means on the whistle device proper and said plate for retaining said plate against accidental displacement.

4. A whistle device composed of two in-

dependently formed parts, one of said parts having a sound chamber and including an angularly disposed mouthpiece portion and the other part comprising a plate mounted over and completing the formation of said sound chamber and mouthpiece and being movable relatively thereto to expose the interior of the sound chamber and mouthpiece for cleaning or other purposes.

5. A whistle device composed of two independently formed parts, one of said parts having a sound chamber and including an angularly disposed mouthpiece portion and the other part comprising a plate mounted over and completing the formation of said sound chamber and mouthpiece and being movable relatively thereto to expose the interior of the sound chamber and mouthpiece for cleaning or other purposes, and said plate including side wall members co-operating with the side wall members of the mouthpiece and sound chamber.

6. A device of the character described comprising a substantially cylindrical sound chamber having a mouthpiece portion disposed angularly with respect to the periphery of said chamber, said device being composed of independently formed parts, one of said parts being movable with respect to the sound chamber and mouthpiece portion of the other part and normally mounted upon and forming a part of the structure thereof and rendering the interior of the sound chamber and mouthpiece accessible for cleaning or other purposes.

7. A device of the character described comprising a substantially cylindrical sound chamber having a mouthpiece portion disposed angularly with respect to the periphery of said chamber, said device being composed of independently formed parts, one of said parts being movable with respect to the sound chamber and mouthpiece portion of the other part and normally mounted upon and forming a part of the structure thereof and rendering the interior of the sound chamber and mouthpiece accessible for cleaning or other purposes, and means for retaining said parts against accidental displacement.

8. A device of the character described comprising a substantially cylindrical sound chamber having a mouthpiece portion disposed angularly with respect to the periphery of said chamber, said device being composed of independently formed parts, one of said parts being movable with respect to the sound chamber and mouthpiece portion of the other part and normally mounted upon and forming a part of the structure thereof and rendering the interior of the sound chamber and mouthpiece accessible for cleaning or other purposes, means for retaining said parts against accidental displacement, and said first named part including a discharge aperture arranged in predetermined position with re-

spect to the sound chamber and inner discharge end of said mouthpiece.

9. A device of the character described comprising a substantially cylindrical sound chamber having a mouthpiece portion disposed angularly with respect to the periphery of said chamber and having flat parallel side walls, said sound chamber and mouthpiece being open at the top, and a part movable with respect to the top of the sound chamber and mouthpiece and normally forming part of said device and rendering the interior of the sound chamber and mouthpiece accessible for cleaning or other purposes when said part is in open position.

10. A device of the character described comprising a sound chamber and a mouthpiece, said sound chamber and mouthpiece being characterized by a top plate, said plate 20 being movable with respect to and completing the formation of said sound chamber and mouthpiece.

11. In testimony that I claim the foregoing as my invention I have signed my name this 25 26th day of January, 1929.

EDWARD R. PETRIE.
